James S. Harkins.

By Paul & Mennin Attys

UNITED STATES PATENT OFFICE.

JAMES S. HARKINS, OF MINNEAPOLIS, MINNESOTA, ASSIGNOR OF ONE-HALF
TO JACOB MERRITT, OF SAME PLACE.

HEATER.

SPECIFICATION forming part of Letters Patent No. 425,222, dated April 8, 1890.

Application filed November 19, 1889. Serial No. 330,912. (No model.)

To all whom it may concern.

Be it known that I, JAMES S. HARKINS, of Minneapolis, in the county of Hennepin and State of Minnesota, have invented certain Improvements in Heaters, of which the following is a specification.

This invention relates to improvements in stoves or furnaces designed for heating or cooking purposes; and the objects I have in view are to provide means for producing a large supply of heat with a small supply of fuel and consuming the smoke and products of combustion that in the ordinary furnaces or stoves are passed into the smoke-flue in the form of gases.

To these ends the invention consists, generally, in the construction and combination hereinafter described, and particularly pointed out in the claims.

In the accompanying drawings, forming a part of this specification, Figure 1 is a vertical section of a stove or furnace embodying my invention. Fig. 2 is a horizontal section of the same on line *x x*. Fig. 3 is a horizontal section on line *y y* of Fig. 1, and Fig. 4 is a horizontal section on line *z z* of Fig. 1.

In the drawings, 2 represents the outer shell or casing of the heater, and 3 represents the fire-pot, which preferably occupies a central position therein and is provided with a suitable grate 5. The lower portion of the fire-pot, above the grate, is provided with a sloping wall 7, having openings 9 arranged above the surface of the grate. An ash pit or box 11 is located below the grate 5, being inclosed by a wall 13, that extends to the top of the inclined wall 7, that forms the lower part of the fire-pot. The ash-box is provided with an extension 15, extending through the front of the casing, and provided with a suitable door 17, having a draft-opening therein, and provided with a slide 19. The fire-pot 3 is provided above the inclined wall 7 with a vertical wall 21, having a series of openings 23 arranged in the lower part thereof and above the inclined wall 7. The lower end of the wall 21 is preferably curved outward at the point where it joins the wall 7, as shown in said Fig. 1.

Arranged outside of the vertical wall 13 is a wall 25, the upper portion of which is curved

inwardly and joins the wall 21 of the fire-pot above the openings 23. An annular space is formed thereby between said walls 13 and 25, which forms a diving-flue extending from said openings 23 to the bottom of the furnace, as hereinafter described. This space communicates through openings 27 with an annular chamber 29, arranged in the lower part of the furnace and inclosed on the top and bottom by horizontal plates 31 and 33. A vertical circular wall 35, provided with a series of openings 37, is preferably arranged in the chamber 29, and a flue 39 extends from this inner wall through the rear wall of the furnace and connects with the smoke-flue 41. The chamber 29 is also provided with an extension 38, having a door 43 at the front of the furnace.

Beneath the chamber 29 is a chamber 45, with which the cold-air duct 47 communicates. The chamber 45 communicates with the annular space 49 between the wall 25 and the wall of the casing 2, and this annular space extends nearly to the top of the furnace, as shown in Fig. 1.

Between the chamber 29 and the ash-box 11 is a chamber 51, having a series of transverse division-plates 53 extending partially across said chamber. The space 49 communicates with this chamber by means of a short horizontal pipe 55, and a pipe 57 forms an exit to the chamber at the other side thereof, extending through the casing of the furnace and connecting with the vertical pipe 59, that extends to a point near the top of the furnace and communicates with the hot-air chamber 85 therein, as hereinafter described.

Above the fire-pot 3 is a chamber 4, having a flue 6, that communicates with the smoke-pipe 41 and is provided with a suitable damper 8. This chamber extends to the front of the furnace, where it is provided with a door 10, having a suitable draft-opening and a slide 12.

Above the chamber 4 is a chamber 14, having in its outer wall a series of openings 16, which communicate with the space 49. A spiral division-plate 18 is arranged in this chamber, thereby forming a spiral passage extending from the circumference to the center of the chamber, at which point there is an opening 20, communicating with the hot-

air chamber or dome 22, that forms the top of the furnace. An annular water-pan 24 is arranged in this chamber and surrounds the opening 20.

5. A chamber 26 is arranged on the outside of the furnace and communicates with the bottom of the pan 24 through a suitable pipe 28. The chamber 26 is provided with a suitable cover 30, and its wall is preferably a little lower than the walls of the pan 24. The pan is filled with water by pouring it into the chamber 26, and before the pan will overflow the water will run over the top of the chamber 26. The vertical pipe 59, hereinbefore referred to, is provided at its top with a horizontal extension that passes through the water-pan 24 into the central space thereof, as shown in Fig. 1. The dome 22 is also provided with openings 32, to which suitable hot-air pipes may be connected for the purpose of leading the heated air to the rooms or apartments that are to be heated.

Operation: In starting the fire, or when it is desired to obtain a direct draft, the damper 8 may be opened and the slides in one or both of the doors 10 and 17. There will then be a direct draft from the fire-pot through the pipe 6 into the smoke-flue. After the fire is well under way the damper 8 is closed, and the draft will then be through the openings 23, down through the diving-flue, and into the smoke-pipe through the chamber 29. The downward draft from the fuel-door 10 through the fuel in the fire-pot to the openings 23 will carry the smoke and products of combustion downward over and through the ignited coal in the lower part of the fire-pot, causing the smoke and unconsumed gases to be consumed. The upward draft through the grate will cause the fuel in the lower part of the fire-pot to remain ignited. By this means I am enabled to obtain a substantially perfect combustion of the fuel. The cold air, which is brought through the flue 47 and carried into the space 49, after passing through the chamber 45, goes upward in this space, and a part of it passes into the chamber 51, and after passing through that chamber, where it becomes heated, passes through the pipes 57 and 59 upward, and then into the hot-air chamber 22, being delivered in said chamber inside of the annular water-pan 24. The remaining air in the space 49 passes upward in said space, and then into the chamber 14 through the opening 16, and after passing through said chamber is delivered through the opening 20 into the center of the chamber 22. All of the heated air that is brought into the chamber 22 must first pass over the top of the pan 24, and in doing so it becomes charged with moisture therefrom, and in this condition is ready to pass into the pipes leading to the apartments. It will be seen that this construction will secure a very perfect combustion of the fuel, and that the air will be brought to a high temperature by the time that it reaches the hot-air chamber,

from which it is passed to the apartments to be heated. It will also be seen that this construction may be used in any kind of a stove or heater.

70

I claim—

1. In a heater, the combination, with a suitable fire-pot having a series of openings in its wall, of a grate, an ash-box below said grate, provided with a draft-opening, a fuel-door above said fire-pot, also provided with a draft-opening, and an annular wall forming a diving-flue surrounding said fire-pot, with which the openings in the wall of the fire-pot communicate, said annular wall extending inwardly at its upper end and abutting against the wall of the fire-box above said openings, substantially as described.

2. The combination, in a furnace or heater, with a fire-pot having a suitable grate, and having a series of openings in its wall, and with a draft-opening above said fire-pot and another one below the grate, of an annular wall forming a diving-flue surrounding said fire-pot, with which the openings in the wall communicate, said annular wall abutting against the wall of the fire-box above said openings, and a smoke-flue with which said diving-flue communicates, substantially as described.

3. In a heater, the combination, with the fire-pot 3, provided at its lower portion with the inclined wall 7 and at its upper portion with the vertical wall 21, having the series of openings 23, and with suitable draft-openings above said fire-pot and below said grate, of the annular wall 25, arranged outside of said fire-pot and forming a diving-flue, having its upper end abutting against the wall of the fire-box above said openings, the chamber 29, with which said diving-flue communicates, and the smoke-flue connected with said chamber.

4. The combination, with the fire-pot having openings in its wall, of an annular wall having its upper end abutting against the wall of the fire-pot above the openings therein and forming a diving-flue, with which said openings communicate, communicating with a suitable smoke-flue, a direct flue above said fire-pot, also communicating with said smoke-flue and provided with a suitable damper, and suitable draft-openings arranged above and below said fire-pot, substantially as described.

5. The combination, in a heater, with the fire-pot having openings in its wall, of a diving-flue surrounding said fire-pot, with which said openings communicate, the chamber 29, with which said diving-flue communicates, provided with the vertical wall 35, having openings 37, and with the door 43, the smoke-flue 41, and the pipe 39, connecting said chamber with said smoke-flue, substantially as described.

6. The combination, with the fire-pot and the diving-flue surrounding said fire-pot, of the casing 2, forming an air-space 49 outside of

said diving-flue, and the chamber 14, arranged above said fire-pot and connected with said air-space and having the spiral division-plate 18 therein, substantially as described.

- 5 7. The combination, in a heater having a suitable fire-pot and an annular diving-flue surrounding said fire-pot, of a casing arranged outside of said diving-flue, and chambers 14 and 51, arranged, respectively, above and below said fire-pot, and the hot-air dome 22, the said chamber 14 communicating with the space 49 and with said drum, and chamber 51 communicating with the drum through pipe 59, and also with space 49, substantially as described.
- 10 8. The combination, with the fire-pot 3 and

the chamber 4, arranged above said fire-pot, of the casing 2, surrounding said fire-pot and inclosing a suitable air-space, the chamber 14, arranged above said chamber 4 and provided with a spiral division-plate and having an opening 20 at its center, and a chamber 22, arranged above said chamber 14 and provided with the annular water-pan 24, surrounding said opening 20.

In testimony whereof I have hereunto set my hand this 8th day of November, 1889.

JAMES S. HARKINS.

In presence of—

A. C. PAUL,

A. M. GASKILL.
